Anne Doster, Downsview, Ontario, Canada, assignor to
Tycos Tool & Die Company Limited, Toronto, Ontario,
Canada, a corporation of Canada

Filed Aug. 30, 1963, Ser. No. 76,421

Term of patent 3½ years

(Cl. D48—16)

FIG. 1

FIG. 2

FIG. 3

FIG. 1 is a perspective view of a prismatic reflector showing my new design. It is to be understood that the prismatic design which is partially shown in full lines continues uniformly throughout the broken line area thereof.

FIG. 2 is a sectional view taken along line 2—2 of FIG. 1, and

FIG. 3 is a plan view showing the back of the reflector.

I claim:

The ornamental design for a prismatic reflector, as shown and described.
